[57] CLAIM

The ornamental design for a combined beer light and key holder, as shown and described.

DESCRIPTION

FIG. 1 is a perspective view of a combined beer light and key holder showing my new design;

FIG. 2 is a top plan view thereof;

FIG. 3 is a bottom plan view thereof; and

FIG. 4 is a side elevational view, the opposite side being substantially a mirror image thereof. The environmental matter shown in dotted lines are for illustrative purposes only and not a part of the design claimed.

FIG 2

FIG 4
